DESIGN FOR A SHOE

Helen B. Kozak, New York, N. Y., assignor to Laird, Schober Company, Inc., Philadelphia,
Pa., a corporation of Pennsylvania

Application December 14, 1935, Serial No. 60,089

Term of patent 3½ years

To all whom it may concern:

Be it known that I, Helen B. Kozak, a citizen of the United States, residing in New York, county of New York and State of New York, have invented a new, original, and ornamental Design for a Shoe, of which the following is a specification, reference being had to the accompanying drawing forming a part thereof, in which

Fig. 1 is a plan view of a shoe showing my new design; and

Fig. 2 is a side elevation thereof.

I claim:—

The ornamental design for a shoe, substantially as shown.

HELEN B. KOZAK.
